TOWED GLIDER

Russell M. Carlson, Milford, Conn., assignor to
 United Aircraft Corporation, East Hartford,
 Conn., a corporation of Delaware

Application June 15, 1946, Serial No. 676,989

19 Claims. (Cl. 244—3)

1

This invention relates to a towed winged target adapted to be utilized for anti-aircraft and fighter practice and other towed gliders such as cargo gliders.

A principal object of the invention is to provide a high speed glider target which can be towed in an offset position relative to the towing plane during target practice and which can be towed in an in-line position during take-off and landing of the target. Similarly, other gliders, such as cargo gliders, may be towed in substantially an in-line position during take-off and landing and in an offset position during flight, especially where two or more gliders are to be towed.

Another object of the invention is the provision of means for controlling the movement of the towed glider between its in-line and off-set positions.

A further object of the invention is the provision of improved mechanism carried by the glider for shifting the glider from its off-set to its in-line relation, or the reverse, which is responsive to the will of the pilot in the towing plane.

It is a further object of the invention to provide a towed target or glider of the above type having self-contained mechanism for automatically controlling the movement of the glider between its in-line and offset positions; and more specifically to provide mechanism which is responsive to the speed at which the glider is towed to control its position relative to the line of flight of the towing plane.

Other objects of the invention are the provision of a towed glider which in its configuration generally resembles the conventional airplane and one which has simple and reliable control mechanism completely housed within the fuselage of the glider for shifting the glider between its different flight positions.

These and other objects and advantages of the invention will become evident from the following detailed description of one embodiment of the invention shown in the accompanying drawings.

In these drawings:

Fig. 1 is a perspective view of a towed winged glider embodying the invention shown in offset position relative to the line of flight of the towing plane;

Fig. 2 is a partial front view of the target shown in Fig. 1;

Fig. 3 is a transverse section through the nose of the target taken on lines 3—3 of Fig. 4 and looking forward in the direction of the arrows;

2

Fig. 4 is a view looking at one of the tow bar assemblies, the fuselage being shown in section on line 4—4 of Fig. 2; and

Fig. 5 is a diagrammatic showing of the circuit connections for the reversible electric motor and the control switches therefor.

As herein shown, the towed glider generally indicated in Fig. 1 by the numeral 10 comprises a long cylindrical fuselage 12 supporting two wings 14 and 16 located substantially midway between the fore and aft ends of the fuselage, two tail surfaces 18 and 20 located at the extreme aft end of the fuselage and two tow bar assemblies 22 and 24 located at the extreme forward end of the fuselage.

Each wing panel comprises a leading edge assembly 26 and a trailing edge assembly 28 which are detachably secured together by piano hinges. The entire wing assembly is interchangeable, left and right, and is fastened to the fuselage by bolts, not shown, so that in service a damaged wing may be quickly repaired by a standard wing part.

The tail surfaces 18 and 20 are similar in construction to the wing, comprising leading edge assemblies 30 and trailing edge assemblies 32 connected by piano hinges. Each tail surface 18 and 20 is detachably bolted to the fuselage and these surfaces, like the wings, are interchangeable left and right. It will be noted from Fig. 1 that the wings 14 and 16 have a slight dihedral angle while the tail surfaces 18 and 20 and the tow assemblies 22 and 24 are disposed at very sharp dihedral angles of approximately 32°. An empennage of horizontal and vertical surfaces familiar to those skilled in the art of aircraft may be employed as an alternate for the V-type tail surfaces shown.

The tow bar assemblies 22 and 24 are carried by a fuselage nose section 34 best shown in Fig. 4 and comprise identical tubular tow posts, or bars, 36, the inboard ends of which have fittings 38 secured rigidly in a solid nose portion 40. Each of these tow bars has an outboard and fitting, or cap, 42 of streamlined cross section extending fore and aft thereof. These outboard fittings are supported by tension cables 44 (Fig. 2) extending inboard and aft therefrom to the fuselage nose section 34 for the purpose of supporting the tow bars against bending moments caused by the tow cable and by the trailing control surfaces 45, 46 carried by the tow bars. For target glider use, the fuselage nose section 34, housing the offset position operative mechanism, may be made

of cast iron as a protection for the mechanism against the bullets fired at the target.

The trailing control surfaces 45, 46 are supported by piano hinges, the forward hinge strips 47 of which are secured to the tow bars 36 substantially along the entire length thereof, as by rivets 48, and the rear hinge strips 49 of which are secured to the lower surface of the control surfaces 45, 46 at the leading edge thereof. These piano hinges are similar to those previously mentioned in connection with the wing and tail surface assemblies.

The target is adapted to be towed behind the towing plane by means of a V-bridle 52 trailing behind a tow cable 54 suitably attached to the towing plane. The ends of the bridle 52 pass through cable sheaves 56 supported in brackets 58 on the forward ends of fittings 42 and then pass through transverse conduits 62 which are supported on the leading edges of the tow bars 36 by clips 64. These cable ends are attached to the opposite ends of a chain 66 which passes beneath a central sprocket 68 mounted in the rigid portion 49 of the fuselage nose in the central longitudinal plane of the fuselage. The sprocket 68 is driven by a reversible electric motor 70 which, through the action of the sprocket 68 on the chain 66, offsets the bridle 52 from a symmetrical position thereof relative to the tow bars 22 and 24, in which the vertex 53 of the bridge 52 and the towing cable 54 lie in the symmetrical axis 72 parallel to the longitudinal axis of the glider 10, into an offset position such as shown in Fig. 1. It will be understood that, while Fig. 1 shows the glider being towed in an offset position at an angle of 35° to the line of flight of the towing airplane, the angle of the offset tow position may be varied in some installations or may be pre-set by limiting the travel movement of control surfaces 45, 46.

The control surfaces 45, 46 on the tow bars are also simultaneously operated by the same electric motor 70. To this end the motor 70 has a pinion gear 74 which meshes with a sector gear 76 rotatable about a pivot pin 78 suitably supported in the nose structure as by the clip 80 and fixed bar 82. A control surface actuating arm 84 which is also pivoted on the pivot pin 78 and is fixed to the sector gear 76 by rivets 86 extends through a slot 88 in the nose fitting 34. The free end of actuating arm 84 is pivotally connected at 90 to oppositely directed control surface actuating links 92 and 94 by means links 96 and 98. The links 92 and 94 are pivotally connected at their outboard ends respectively by links 99 and 99a to the inboard ends of the swivel studs 100 and 102 which extend through the control surfaces 45, 46. The connection between the arm 84 and the control surfaces is such that, by lateral movement of the arm about its pivot 78 from the full line position into the dotted position shown in Fig. 3, the control surfaces on the tow bars will be operated into the Fig. 2 position in which the port surface (shown as the right hand surface 45 in Fig. 2) is deflected outboard and downwardly and the starboard surface (shown as the surface 46 in Fig. 2) left hand is deflected inboard and upwardly. The above described movement of the control surfaces will result in the glider assuming an offset position to starboard but by providing for the opposite movement of the surfaces, an offset position to port may be obtained. In the position of the parts of the control surface assembly shown in Fig. 3 the two control

surfaces 45, 46 are both in their neutral, or undeflected, positions.

The control arm 84 in its vertical position shown in Fig. 3 is also adapted to engage the operating member 104 of a normally closed electric limit switch A, which is supported on a bracket 106 of the fixed nose structure, and hold this switch in its contact open position. A similar electric limit switch B is mounted on bracket 108 on the fixed nose structure in position to be engaged by arm 84 in the other extreme position of this arm shown dotted in Fig. 3 in which position of arm 84 the operating member 106 of the switch B is depressed into contact open position. The switches A and B, which are shown diagrammatically in Fig. 5, are identical, the switch A comprising stationary contacts 112 and movable contact bridging member 116 which is constantly biased into engagement with the stationary contacts 112 by compression spring 118. Switch B comprises the stationary contacts 118, a cooperating movable contact bridging member 120 and a compression spring 122 which constantly biases the bridging member 120 into engagement with the stationary contacts 118.

The motor control circuit shown in Fig. 5 also includes a third switch C which is a double throw starting switch including an operating member 126 and a movable contact bridging member 128 adapted to bridge two spaced sets of stationary contacts 128 and 130, a compression spring 132 being provided to normally maintain the bridging member 126 in engagement with the stationary contacts 128.

35 The switch C is supported on the fixed nose structure 34 by a suitable bracket 134 with its operating member 126 beneath the hinged bracket 136 of a drag flap 138 which is pivoted at 140 on the fixed nose structure 34. The hinged bracket 136 has an ear 142 extending forwardly of its pivot 140 and a compression spring 144 is provided between this ear and a pad 146 on the nose structure for constantly biasing the flap 138 into the elevated position shown in Fig. 4 in which it projects above the streamlined surface of the fuselage 12 into the airstream. It will be evident from Fig. 4 that whenever a sufficient force is exerted on the drag flap 138 by the airstream this flap will be moved against the action of the spring 144 partially into a recess 148 in the fuselage skin. The flap will not be depressed to a position where it will be entirely flush with the fuselage skin for, in that position, it would lose its air loading. It will also be evident that in the flush position of the flap 138 the end portion 150 of the bracket 136 will have engaged and depressed the operating member 126 of switch C into its lowermost position in which it bridges the contacts 139.

60 As shown in Fig. 5 the reversible motor 70 has two sets of terminals 152 and 154. The terminals 152 are connected to the negative terminal of the battery 156 by conductors 158 and 160 respectively while the terminals 154 are connected through parallel conductors 162 and 164 with the positive terminal of the battery. From Fig. 5 it will be noted that the contacts 112 of the limit switch A are connected in conductor 162 while the similar contacts 118 of limit switch B are connected in conductor 164. Also the double throw switch C has its stationary contacts 128 connected in conductor 162 and its contacts 130 connected in conductor 164. These circuit connections are such that upon completing the circuit through conductor 162 the motor 70 will

rotate in one direction, whereas completion of the circuit through conductor 164 will result in its rotation in the opposite direction.

The towed glider is provided with a main landing gear comprising wheels 166 and cantilever leaf springs 168 and with a nose skid 170 best shown in Figs. 2 and 4.

In operation the glider may be launched by a "snatch pick-up" or by a "drag take-off" as desired. In either case upon take-off the parts will be in the positions shown in Figs. 3, 4 and 5 in which the control arm 84 is engaging operating member 104 of limit switch A and holding it open, the drag flap 138 is in raised position and the bridging member 136 of switch C is bridging contacts 128. Limit switch B is closed but conductor 164 is open at contacts 130 of starting switch C. Also, the control arm 84 being in its vertical position shown in Fig. 3, the control surfaces 45, 46 on the tow bars are in their neutral, undeflected positions and the chain 66 is in a position on the sprocket 68 such that the two branches of the V-bridle 52 between the point 53 and the cable sheaves 56 are of equal length. Accordingly, the glider will, during the take-off, be directly in line with the towing plane in the usual manner and it will continue to maintain this in-line position until the relative airspeed is reached at which the flap 138 is depressed, by the air loads acting thereon, to a position sufficient to operate the control surface actuating mechanism.

The movement of the glider to offset position is controlled by the pilot of the towing plane by controlling the speed at which the glider is towed, the critical speed at which offsetting of the glider takes place being determined by the choice of spring 144. Below the selected critical speed, which may be by way of example a speed of 150 miles an hour, the drag flap 138 will remain in the elevated position shown in Fig. 4, but when the predetermined speed has been reached this flap will be depressed to move the bridging member 136 of starting switch C out of engagement with contacts 128 and into engagement with contacts 130. Closing of contacts 130 will result in completing the circuit from battery 156 through conductor 164, switch C at contacts 130, switch B at contacts 118 to one of the motor terminals 154 and from the corresponding terminal 152 through conductor 160 to the negative terminal of the battery. The motor will operate to move the chain 66 so that one branch of the V-bridle will be shortened and the other lengthened until point 53 of the bridle has been displaced into the offset position shown in Fig. 1. Simultaneously the gear 74 of the motor will have moved the sector gear 76 and its attached arm 84 into the dotted position of the latter shown in Fig. 3 in which it engages the operating member 110 of limit switch B, resulting in the opening of the circuit above traced and the de-energization of the motor.

As long as the pilot flies the glider above the selected critical speed the starting switch C will remain with its movable contact member 126 bridging contacts 130 and, since the conductor 162 is now open at switch C and the conductor 164 is open at switch B, the parts will remain in this position. When it is desired to resume in-line flight conditions to make a landing the pilot merely reduces his speed and consequently the speed of the glider below the critical speed, allowing the drag flap 138 to rise and close the motor circuit through conductor 162 at contacts 128 of switch C, whereupon the motor will run in the reverse direction and return the parts to their original positions.

It will be evident that as a result of this invention a towed target has been provided which generally simulates an airplane in appearance and flight characteristics and which is capable of being towed at high speed. Further, automatically operative mechanism has been provided for take-off and landing of the target in an in-line position relative to the towing plane while permitting offset flight of the target during target practice. Similarly, it is evident that, with the invention described, two or more gliders, such as cargo gliders, may be towed in substantially in-line or only slightly offset positions during take-off or early flight and landing and that operative mechanism has been provided to have the gliders assume a greater offset position relative to the line of flight of the towing airplane during higher speed.

The advantages of offset towing of the glider when it is used as a target will, it is believed, be obvious since it permits the simulation of actual combat involving attack from the front and rear of the target by fighter planes without endangering the towing plane and its pilot who would otherwise be in the line of fire.

It will further be evident that by this invention a particularly simple and effective mechanism has been provided by which the pilot of the towing airplane can control the movement of the towed glider between in-line and offset positions, yet does not require any control apparatus which is not wholly contained in the glider.

While only one embodiment of the invention has been illustrated and described it will be evident that numerous changes in the construction and arrangement of the parts may be made without departing from the scope of the appended claims.

What it is desired to secure by Letters Patent is:

40. 1. A glider adapted to be towed by a powered airplane, a movable control surface on said glider, and means governed by the speed of said glider for moving said control surface to shift said glider from an in-line position to an offset position relative to the line of flight of the towing airplane.
45. 2. A glider adapted to be towed by a powered airplane, means carried by said glider for shifting the latter between an in-line position and an offset position relative to the line of flight of the towing airplane, and means governed by the speed of said glider for controlling said shifting means.
50. 3. A glider adapted to be towed by a powered airplane and including a tow cable connection to said glider, a pair of control surfaces, and means governed by the speed of said glider for shifting said glider from an in-line position to an offset position relative to the line of flight of the towing airplane including means for controlling the deflection of said surfaces.
55. 4. A glider adapted to be towed by a powered airplane and including a tow cable connection to said glider, a pair of control surfaces and means governed by the speed of said glider for shifting said glider from an in-line position to an offset position relative to the line of flight of the towing airplane including means for moving said surfaces between a neutral position and a deflected position thereof.
60. 5. A glider adapted to be towed by a powered airplane and including a tow cable connection to said glider, a pair of control surfaces, and means governed by the speed of said glider for shifting said glider from an in-line position to an offset position relative to the line of flight of the towing airplane including means for simultaneously
65. 70. 75.

shifting said tow cable connection and moving said control surfaces.

6. A glider adapted to be towed by a powered airplane and including a tow cable connection to said glider, a pair of control surfaces, and means for shifting said glider between an in-line position and an offset position relative to the line of flight of the towing airplane including power operated means carried by said glider for simultaneously laterally shifting said tow cable connection and for deflecting said control surfaces.

7. A glider adapted to be towed by a powered airplane and including a tow cable connection to said glider, a pair of control surfaces, and means for shifting said glider between an in-line position and an offset position relative to the line of flight of the towing airplane including power operated means controlled by the pilot in the towing airplane for simultaneously deflecting said surfaces and laterally shifting said tow cable connection, said power operated means including a drag flap carried by said glider and controlling said glider shifting means.

8. A glider adapted to be towed by a powered airplane and including a tow cable connection to said glider, a pair of control surfaces, and means for shifting said glider between an in-line position and an offset position relative to the line of flight of the towing airplane including power operated means for simultaneously laterally shifting said tow cable connection and for operating said control surfaces, said power operated means including a motor, a source of motive power, controlling mechanism therefor, and means including a drag flap governing the operation of said controlling mechanism.

9. A glider adapted to be towed by a powered airplane and including a fuselage, wing and tail surfaces supported by said fuselage, a tow cable connection to said glider forward of said wing surfaces, pivotally supported trailing control surfaces adjacent the forward end of said fuselage, means for shifting said glider between an in-line position and an offset position relative to the line of flight of the towing airplane including a drag flap on said glider, and means operated by said flap for simultaneously laterally shifting said tow cable connection relative to said glider and for operating said control surfaces.

10. A glider adapted to be towed by a powered airplane and including a fuselage, sustaining surfaces supported by said fuselage intermediate the ends thereof, bridle posts carried by the forward portion of said fuselage, control surfaces pivotally mounted on trailing edges of said bridle posts, tow cable connections including a V-bridle carried by said posts and a common operating means for effecting lateral displacement of the vertex of said V-bridle and for effecting deflection of said surfaces.

11. A glider adapted to be towed by a powered airplane and including a fuselage, sustaining surfaces supported by said fuselage intermediate the ends thereof, bridle posts carried by the forward portion of said fuselage, control surfaces pivotally mounted on trailing edges of said bridle posts, tow cable connections including a V-bridle carried by said posts, and a common operating means for effecting lateral displacement of the vertex of said V-bridle and for effecting deflection of said surfaces, and speed responsive means for controlling said operating means.

12. A glider adapted to be towed by a powered airplane and including a tow cable connection to said glider, a pair of movable control surfaces movable between a neutral position and a de-

flected position for shifting said glider from an in-line position to an offset position relative to the line of flight of the towing airplane, and means including a pivoted drag flap responsive to the speed of said glider for controlling the movement of said surfaces.

13. A towed glider including a fuselage, sustaining surfaces supported by said fuselage intermediate the ends thereof, bridle posts carried by the forward portion of said fuselage, control surfaces pivotally mounted on the trailing edges of said bridle posts, a V-bridle having its vertex normally disposed in the line of flight of the glider, means carried by the glider for shortening one leg of said bridle and lengthening the other, whereby to permit said glider to fly in an offset position relative to the line of flight of the towing airplane, and means governed by the speed of the glider for controlling the operation of said first mentioned means.

14. A towed glider including a fuselage, main sustaining surfaces supported by said fuselage intermediate the ends thereof, bridle posts carried by the forward portion of said fuselage, control surfaces pivotally mounted on the trailing edges of said bridle posts, a V-bridle connected to said posts, means for shifting said target between an in-line position and an offset position relative to the line of flight of the towing airplane including mechanism for changing the relative length of the arms of said V-bridle, and means for operating said surfaces.

15. A towed glider including a fuselage, main sustaining surfaces supported by said fuselage intermediate the ends thereof, bridle posts carried by the forward portion of said fuselage, control surfaces pivotally mounted on the trailing edges of said bridle posts, a V-bridle connected to said posts, means for shifting said glider between an in-line position and an offset position relative to the line of flight of the towing airplane including mechanism for changing the relative lengths of the arms of said V-bridle and means for operating said surfaces, and means governed by the speed of the glider for controlling said shifting means.

16. A glider adapted to be towed by a powered airplane and including a tow cable connection to said glider, a pair of control surfaces, a drag flap carried by said glider, and means for shifting said glider between an in-line position and an offset position relative to the line of flight of the towing airplane including means governed by said drag flap for simultaneously shifting said tow cable connection and moving said control surfaces while maintaining unaltered the line of flight of the powered airplane.

17. A glider adapted to be towed by a powered airplane and including a tow cable connection to said glider, a pair of control surfaces, a source of power in the glider, control means carried by the towing airplane and means for shifting said glider between an in-line position and an offset position relative to the line of flight of the towing airplane including power operated means carried by said glider and governed by said control means for simultaneously laterally shifting said tow cable connection and for deflecting said control surfaces while maintaining the original line of flight of the powered airplane.

18. A glider adapted to be towed by a powered airplane and including a tow cable connection to said glider, a pair of control surfaces, and means for shifting said glider between an in-line position and an offset position relative to the line

of flight of the towing airplane including power operated means controlled by the pilot in the towing airplane for simultaneously deflecting said surfaces and laterally shifting said tow cable connection, said power operated means including a drag flap carried by said glider and controlling said glider shifting means while maintaining the original line of flight of the powered airplane.

19. A glider adapted to be towed by a powered airplane and including a tow cable connection to said glider, a pair of control surfaces, and means for shifting said glider between an in-line position and an offset position relative to the line of flight of the towing airplane including power operated means for simultaneously laterally shifting said tow cable connection for operating said

control surfaces, said power operated means including a motor, a source of motive power, controlling mechanism therefor, and means including a drag flap governing the operation of said controlling mechanism while maintaining the original line of flight of the powered airplane.
